UNITED STATES PATENT OFFICE.

PETER COLQUHOUN, OF CLEVELAND, OHIO, ASSIGNOR TO THE AMERICAN MULTIGRAPH COMPANY, OF CLEVELAND, OHIO, A CORPORATION OF OHIO.

SAFETY DEVICE FOR FLAT-BED PRINTING PRESSES.

Application filed March 9, 1925. Serial No. 14,123.

This invention relates to printing presses and is particularly concerned with safety mechanism in connection with a bed and cylinder press for preventing the engagement 5 of the platen with the type bed as a result of prematurely tripping certain latching mechanism associated therewith. This might ordinarily occur either when the platen and the type bed are in a position such that accidental tripping by the operator would result in 10 jamming or suddenly stopping the machine and damaging the moving parts thereof by reason of their inertia, or when lowering the platen would result in fouling the 15 tympan sheet of the cylinder against the inked type.

The general object of the invention is to provide a printing mechanism which shall be efficient and rapid in its operation and in 20 which the operating parts are protected against accidental actuation at any improper time by safety mechanisms.

In the printing press shown in the drawings the type is contained in a flat chase 25 reciprocable beneath a rotating cylinder or impression platen on which a sheet of paper is carried into engagement with the type. The paper is printed during the reciprocation of the type bed in one direction; while 30 the cylinder or platen continues to rotate to eject the printed sheet from the machine during the return travel of the type bed.

Such a press is shown, described and claimed in the application of Lawrence 35 Morse, Serial No. 602,161 filed November 20, 1922 and in the application of Henry C. Osborn, Ser. No. 616,924 filed Feb. 5, 1923. Reference should be made to the latter application in regard to paper controlled, 40 latch-operating mechanism herein shown but not claimed, whereby the movement of the paper as it is drawn by the platen towards the type bed causes the actuation of mechanism which lowers the impression platen into engagement with the type.

In the drawings, Fig. 1 is a plan view of a printing press in connection with which my invention is adapted to operate, certain portions including the paper feeding tray, 50 the inking mechanism and the paper receiving tray, being removed as inessential to the operation of my invention; Fig. 2 is a fragmentary side elevation of the central portion of the printing press; Fig. 3 is a similar side elevation showing the parts in different posi-

tion; Fig. 4 is a similar side elevation showing the parts in still another position; Fig. 5 is a fragmentary cross section through the paper feeding mechanism and showing a portion of the printing cylinder or platen in 60 end elevation.

Referring in detail to the drawings and indicating the various parts by numerals, the general frame of the machine is shown at 1, which frame may be adapted to support the power mechanism and reciprocating gearing (not shown) for the type bed. The frame has flanges 2 at either side which support side frame members 3 and 4 in which is journaled the shaft 5 for the impression platen 6. The platen is arranged to be rotated by a gear 7 shown at the left of the machine in Fig. 1, which may be connected by an Oldham coupling (not shown) to one end of the shaft 5 of the platen. The gear 7 is operated in timed relation to the reciprocation of a type bed 10, which may be driven as shown in the prior application of Morse above referred to or in any manner. The timing of the rotation of the platen and the reciprocation of the type bed is such that the platen rotates twice to every complete (that is forward and backward) reciprocation of the bed, and it may be assumed that the type is inked by suitable ink feeding mechanism such as rollers and an ink fountain at one end of the stroke of the type bed.

My invention consists of a safety latching mechanism adapted to cooperate with a 90 platen retaining latch for holding the platen or printing cylinder in lowered or type engaging position and with an auxiliary latching mechanism which cooperates with the first mentioned latch to hold it in inoperative position when no paper is being fed. This retaining latch for the printing cylinder comprises a plate 20 rigid on one end of the platen shaft and arranged to be turned with relation to the frame, by a link 21 and arms 22 and 23 rigidly secured to a rock shaft 24 journaled in the side frame member 3. The shaft has an eccentric portion 25 as shown in Fig. 2 which causes the raising and lowering of the platen whenever the plate 20 is partially rotated. The position of the plate when the platen is lowered corresponds to Fig. 2, while the unlatched idle position is that shown in Fig. 3.

For lowering the platen, I make use of the 110

reciprocating movement of the type bed, and for raising it, I may employ a spring 30 connecting the plate 20 with the frame 1. For holding the platen in its lowered or printing position, I have shown an abutment 35 carried by the plate 20 which is engaged by the forward end of a latch 36 normally held downward in plate engaging position by a link 37 connected to a bell-crank 38, the lower 10 arm 39 of which engages a shiftable yoke member 40 having pins 41 and 42 rigid therewith which extend through the frame bracket 3. One of these pins namely 42 is equipped with a compression spring (not 15 shown) tending to normally force it outwardly to lower the forward end of the latch 36 into engagement with the abutment of the plate. These pins coat with the lever 23 and with cam members supported by 20 the bed plate during a certain portion of their movement as will be later described.

For holding the latch 36 normally out of engagement with the plate 20 and allowing the spring 30 to raise the platen into inactive position, I employ an auxiliary latching lever having a shoulder 60 adapted to engage a notch 61 in the latch 36. The lever 59 is normally held in engagement with the latch by reason of a tension spring 62 and, 30 when a sheet is fed to the platen, the arm 59 is rotated to the right as shown in Fig. 2 to allow the latch 36 to drop into engagement with the abutment 35 holding the platen in lowered position. This occurs just after the 35 type bed has reached its rearmost position and is returning forwardly beneath the platen. At this time, a pivoted cam 45 carried by the type bed cams upwardly on a roller 46 carried by the arm 23 to rock the 40 plate 20 and lower the platen.

A convenient method of feeding paper to the platen is that shown and claimed in a copending application of Lawrence Morse, Serial No. 14,013, filed March 9th, 1925. 45 This method includes mounting a paper tray such as shown at 70 in front of the machine, and paper may be fed by hand therefrom a sheet at a time as shown in Fig. 5 against stop fingers 71 pivotally mounted in normally rigid frame arm members 72 and 73. These fingers rise in timed relation with the rotation of the platen, and a pair of friction rollers 74 and 75 (one of which is continuously driven) drive the paper forward into engagement with the platen and beneath the upraised fingers. The stop fingers and rolls may be operated by a two-to-one gearing comprising gear members 78 and 79 on the extreme right hand side of the machine, which gearing is arranged to be continuously driven by the platen shaft. The gear 79 carries cams 80 and 81, the latter acting to lower the roller 74 to compress the paper between it and the roller 75 through 60 arms 83 and 84. The former of these arms

is carried rigid with the arm 82 and the latter by a rock shaft 85 which supports the roller carrying arms 86. This rocking movement of the shaft 85 also acts to raise the stop fingers from the path of the paper by a lever 90 which engages a lug 91 rigid with the stop fingers. 70

Suitable mechanism for gripping the forward edge of the paper may include gripper fingers actuated by a gear and sector mechanism 94 and 95 which is in turn operated by a cam 96 rigid with the frame against which a roller 97 on the sector normally bears. The cam is so shaped that the fingers open at various points when the platen cylinder is so rotated with reference to the frame. In the position shown in Fig. 2, the fingers are shown as having engaged the forward edge of the paper and as carrying it around the platen into a position to be printed, and in 85 Fig. 5 the fingers are shown in position about to open to eject the printed sheet.

The mechanism which I have shown for causing the movement of the paper when drawn by the platen gripper fingers to cause the auxiliary latch 59 to disengage the latch 36, when the platen is lowered, is substantially that shown and claimed in the Osborn application above referred to. As the paper is drawn around the platen the 95 cam 80 on the two-to-one gearing operates through an arm 100, rock shaft 101 and a pair of arms 102 to lower a frictional roller 103 against the paper. The roller is turned by the movement of the paper to effect a 100 tripping of the auxiliary latch 59, allowing the latch 36 to operate to hold the platen in lowered position. The movement of the roller 103 is translated through an eccentric 105 disc 105 on the end of the shaft 108 to the upwardly extending arm of the lever 59, carrying it forwardly to the position shown in Fig. 2 to release the latch 36. This releasing occurs only once for each double rotation of the platen. Ordinarily the platen 110 cannot be rotated to its lowered position by the engagement of the cam 45 with the roller on the arm 23 when no paper is fed to the machine because the cam is held up by the pin 41 when the carriage is adjacent its extreme left hand position; but if an accidental tripping of the latch 59 allowed the latch 36 to drop into engagement with the abutment 35 on the plate 20, this would withdraw the pin 41 and allow the cam to drop with the result that the tympan sheet 115 would be brought into direct contact with the inked type. This would result in subsequent offsetting of the wet ink on the tympan sheet to the back of the paper next 120 presented for printing.

Another and often a more disastrous result of the premature tripping of the latch 36 is to suddenly stop the machine. This might happen in case the latch 59 is rotated 125 130

to the right as shown in Figure 4 while the roller on the arm 23 is being returned to its lowermost position by a cam 31 on the rear end of the type bed. A rise 32 on an overhanging cam member 33 ordinarily acts through a projection 34 on the plate 20 to cause the front end of the latch 36 to be forced up into engagement with the latch 59 at the end of the forward stroke of the type bed. But if the latch 59 is withdrawn as mentioned so that the latch 36 may immediately drop down again, the roller on the arm 23 will bump against the cam surface 31 suddenly stopping the machine and perhaps resulting in serious breakage.

The provision whereby I have eliminated these possibilities forms the subject of this invention and the means includes a locking bar or lever 110 pivoted at 111 to the side frame member 3, which lever normally swings by gravity into the path of an abutment member 113 on the latch 36. When the latch 59 is in its active position, as in Fig. 3, the lever 110 does not quite touch the abutment, wherefore the lever may return again to its initial position when raised, as will be presently described. The forward end of the bar 110 is bent as shown in Fig. 1 at 112 to underlie the rearward end of one of the arms 102, and these arms are depressed once for each paper feeding rotation of the platen by the two-to-one gearing and the cam carried thereby is at this time only momentarily raised from engagement with the abutment member 113. Thus if paper is fed and the paper friction roller 103 actuated, the lever 110 is moved out of the way of the abutment on the latch 36 and the latter may function to hold the platen down into active position as shown in Fig. 2. The likelihood of the auxiliary latch 59 being tripped accidentally at this time is very slight and even if it were no more serious damage would ensue than inking the tympan sheet.

The position of the lever 110 is such that it is for the greater part concealed and it would be extremely unlikely for the operator or any one unfamiliar with the machine to tamper therewith and to cause the untimely operation of both the latch 59 and the lever. If either is operated alone to release the latch 36 its operation is effectively counteracted by the other.

I claim:

1. The combination with a printing couple, of two latching devices either of which is effective to control the coaction of the couple, one of said latching devices being manually operable, the other being inaccessible for manual operation.

2. The combination with a type bed and cylinder, of a retaining latch for the cylinder, two latching mechanisms cooperating with the retaining latch and either adapted

to prevent the operation of the retaining latch, one of said latching mechanisms being accessible for manual operation and the other inaccessible.

3. In a bed and cylinder press, the combination with a platen retaining latch, of two latching devices coacting therewith, one of said latching devices being manually operable, the other being inaccessible for manual operation, and mechanism coacting with the paper for operating both of said latching devices.

4. The combination with a printing couple adapted to be inactive, of two latching mechanisms either of which is effective to control the coaction of the couple, mechanism coacting with the paper and adapted to control one of said latching mechanisms.

5. In a safety device for bed and cylinder printing presses, the combination with a platen retaining latch, of a safety latch adapted to prevent the release of the platen retaining latch, an auxiliary latch also adapted to prevent the release of the platen retaining latch, and a device for testing for the presence or absence of paper cooperating with the safety latch.

6. The combination with a bed and cylinder press, of retaining latch mechanism adapted to insure operation, two latching mechanisms cooperating with said retaining latch mechanism and either effective to prevent the release thereof, paper testing mechanism coacting with the two latching mechanisms and adapted to move them both when the paper is present, one of said latching mechanisms being also manually operable.

7. The combination with a printing couple, retaining means for latching one of the members thereof in coaction with the other, two latching mechanisms cooperating with said retaining means, one of said latching mechanisms being periodically released automatically, and the other being manually releasable at any time, whereby the inopportune release of the later mechanism is ineffective.

8. In a printing press of the bed and cylinder type, the combination with a reciprocating bed and a rotary platen adapted to coact with the bed or clear it, of a latch mechanism to retain the platen in active position, an auxiliary latching mechanism cooperating with the retaining latch mechanism to hold the latter mechanism in inactive position, a safety latching mechanism cooperating with the retaining latch mechanism to hold it in inactive position, and means operable by the movement of the paper controlling the auxiliary latching mechanism.

9. The combination with a bed and cylinder, of means for moving the cylinder to active position, a retaining latch for continuing such position, an intermediately

pivoted bar for preventing the operation of the retaining latch, mechanism operating on the paper including parts adapted to move down toward the paper, said bar having a projection extending beneath one of said parts, whereby such projection is lowered and the active end of the bar raised when said mechanism moves down toward the paper to engage it.

10. The combination of a printing couple, positively acting means for bringing the members of the couple together, a latch mechanism adapted when released to allow the operation of said positively acting means, and mechanism to prevent release of the latch mechanism and thereby prevent said means from operating.

11. In a bed and cylinder press, the combination of a reciprocating type bed, a rotary platen adapted to be lowered into coaction with the type bed or raised therefrom, a cam on the type bed, and mechanism operable thereby for positively lowering the platen, a latch mechanism adapted when restrained to hold the cam in idle position and thereby prevent the lowering of the platen, and mechanism to prevent release of the latch mechanism and thereby prevent the cam from operating.

30 12. In a bed and cylinder press, the com-

bination of a reciprocating type bed, a rotary platen adapted to be moved into coaction with the type bed or moved therefrom, a cam on the type bed, mechanism operable thereby for positively moving the platen to 35 active position, a latch mechanism adapted when released to retain such position of the platen, and two latching mechanisms to prevent release of the latch mechanism mentioned, one of said last named latching mechanisms operating automatically at a definite 40 time and the other operable manually at indefinite times.

13. In a bed and cylinder press, the combination of a reciprocating type bed, a rotary platen adapted to be lowered into coaction with the type bed or raised therefrom, a cam on the type bed, mechanism operable thereby for positively lowering the platen, a latch mechanism adapted when 45 released to prevent the raising of the platen, two devices to prevent release of the latch mechanism, and mechanism coacting with the paper to operate one of said devices, that one being manually operable and the other 50 55 inaccessible for manual operation.

In testimony whereof, I hereunto affix my signature.

PETER COLQUHOUN.
